(57) CLAIM

The ornamental design for a water dispenser for pets, as shown and described.

DESCRIPTION

FIG. 1 is a front elevational view of a water dispenser for pets showing my new design;

FIG. 2 is a left side view thereof;

FIG. 3 is a top plan view thereof;

FIG. 4 is a bottom plan view thereof; and,

FIG. 5 is a perspective view thereof.

The broken lines illustrate portions of the water dispenser for pets that form no part of the claimed design.

1 Claim, 5 Drawing Sheets

FIG. 1

FIG. 2

FIG. 4
